(57) **CLAIM**

I claim the ornamental design for a round handle attachment, as shown and described.

DESCRIPTION

A portion of the disclosure of this patent document contains material that is subject to copyright protection. The copyright owner has no objection to the facsimile reproduction by anyone of the patent document or patent disclosure as it appears in the Patent and Trademark office, patent file or records, but otherwise reserves all copyright rights whatsoever.

FIG. 1 is a top and rear side view of the claimed design.

FIG. 2 is a bottom and rear side view of the claimed design.

FIG. 3 is a bottom view of the claimed design.

FIG. 4 is a top view of the claimed design.

FIG. 5 is a front side view of the claimed design.

FIG. 6 is a rear side view of the claimed design.

FIG. 7 is a right side view of the claimed design.

FIG. 8 is a left side view of the claimed design.

FIG. 9 is a bottom view of the claimed design with indication of areas of cross section.

FIG. 10 is a cross-sectional view of the internal surface of the right side of the claimed design according to the presentation of FIG. 9.

FIG. 11 is a cross-sectional view of the internal surface of the front side of the claimed design according to the presentation of FIG. 9.

FIG. 12 is a bottom view of the claimed design with indication of areas of cross section.

FIG. 13 is a cross-sectional view of the internal surface of the left side of the claimed design according to the presentation of FIG. 12; and,

FIG. 14 is a cross-sectional view of the internal surface of the front bottom side of the claimed design according to the presentation of FIG. 12.
